UNITED STATES PATENT OFFICE.

JACOB S. BROWN, OF LOS ANGELES, CALIFORNIA, ASSIGNOR TO WALTER F. EICHEN-HOFER, OF LOS ANGELES, CALIFORNIA.

WELL-CASING APPARATUS.

1,195,906.

Specification of Letters Patent. Patented Aug. 22, 1916.

Application filed October 23, 1915. Serial No. 57,538.

To all whom it may concern:

Be it known that I, JACOB S. BROWN, a citizen of the United States, residing at Los Angeles, in the county of Los Angeles and State of California, have invented new and useful Improvements in Well-Casing Apparatus, of which the following is a specification.

This invention is an improved well casing apparatus especially adapted for use for holding a well casing as the same is being installed in a well and to enable the sections of the casing to be successively jointed together.

15 The invention consists in the construction, combination and arrangement of parts hereinafter described and claimed.

In the accompanying drawings:—Figure 1 is a side elevation of a well casing apparatus constructed in accordance with my invention. Fig. 2 is a plan of the same. Fig. 3 is a vertical sectional view of the same on the plane indicated by the line *a—a* of Fig. 2. Fig. 4 is a detail perspective view of 25 one of the clutching slips.

The spider 1 through which the well casing is lowered is provided with a downwardly tapered central opening 2 and in accordance with my invention is provided on 30 its upper side with a ring 3 which has an outer upstanding annular flange 4 and is also provided with downturned lugs 5 which engage around the spider and are provided with securing screws 6, which serve to detachably secure the ring on the spider. The ring is also provided with spaced pairs of upwardly and outwardly inclined radial arms 7 which are provided with bearings 8. I also provide flexible shafts 9 which comprise members 10 that are mounted in the bearings 8 and members 11 which connect the members 10. Each member 10 is provided at its ends with forks 12. Each member 12 is provided with forks 13 which are arranged at right angles to the forks 12. Blocks 14 are interposed between the forks 12—13 and are connected to said forks respectively by pivot pins 15—16 which are here shown as spider pins. Hence universal 40 joints are formed between said shafts. A series of segmental clutching slips 17 are arranged for vertical and also for radial movement in the spider and are provided with inclined outer sides 18 corresponding 45 with the wall of the opening 2 of the spider

and said clutching slips are provided with teeth 19 on their inner sides presenting sharpened edges. These clutching slips when moved downwardly in the opening of the spider are adapted to engage tightly 50 around the casing and hence support the latter. Certain of the shaft members 10 are provided each with a central opening to receive a rock arm 20, said rock arm having a fork 21 at its inner end pivotally connected by a pin 22 to a lug 23 at the center on the upper side of one of the clutching slips, said lugs having slots 24 in which the said pivoting pins operate so that the slots allow 55 for vibration of the rock arms and form a jar-link to loosen the clutching slips from the casing in the event they should stick thereon. The rock arms are adjustably secured to the shaft members 10 by means of set screws 25.

One of the shaft members 10 is also provided with an upwardly extending lever arm which is connected to an operating lever 27 by a connecting rod 28. The said connecting rod comprises a tubular member 29 60 which has a fork 30 at its outer end pivotally connected to the lever and also comprises a member 31 which is telescopically arranged in the tubular member, is secured thereto in adjusted position by a set screw 33 and is provided at its inner end with a fork 34 which is pivotally connected as at 65 35 to the lever arm.

In the operation of my improved apparatus when the casing A is raised so that 70 the slips are relieved of its weight the slips are raised out of the tapered hole in the spider and held in elevated position until the casing is let down far enough to take on the next joint. The slips are then dropped 75 down in the tapered hole in the spider to hold the casing until the next joint is connected. To prevent the casing from turning an abutment 36 is provided in the spider which is arranged between two of 80 85 90 95 100 the clutching slips.

Having thus described my invention, I claim:—

1. In an apparatus of the class described a spider having a downwardly tapered opening, a ring secured on the spider and provided with bearings, a flexible shaft arranged around the ring and mounted in said bearings, rock arms radially arranged and connected to the flexible shaft for rocking 105 110

motion thereby, means to turn the shaft and impart oscillating motion to the rocking arms and segmental clutching slips arranged vertically and for radial movement in the 5 tapered opening of the spider and connected to and operated by said rock arms.

2. In an apparatus of the class described a spider having a downwardly tapering opening, a ring secured on the spider and having 10 pairs of radially arranged arms provided with bearings, a flexible shaft arranged around the ring and mounted in said bearings, a lever arm connected to said shaft, means to operate the lever arm and 15 thereby rock said shaft, radially arranged rock arms attached to and operated by the shaft, and segmental clutching slips arranged for radial and vertical movement in the opening in the spider and attached to 20 said rock arms.

3. In an apparatus of the class described a spider having a downwardly tapered open-

ing, a ring secured on the spider and having bearing members, a flexible shaft arranged around the ring and comprising 25 members mounted in said bearings and connecting members between the first named members, rock arms radially arranged and attached to certain of the shaft members which are mounted in the bearings for segmental clutching slips arranged for vertical and radial movement in the opening of the spider and attached to and operated by said rock arms, and an abutment in the spider arranged between two of the segmental 30 clutching slips to prevent the clutching slips from turning.

In testimony whereof I affix my signature in presence of two witnesses.

JACOB S. BROWN.
